United States Patent Office

Des. 222,284

Patented Oct. 12, 1971

222,284

VEHICLE TOY

John Edward Walker, 7637 White Oak Ave.,
Reseda, Calif. 91335

Filed Aug. 28, 1970, Ser. No. 24,744

Term of patent 14 years

Int. Cl. D21—01

U.S. Cl. D34—15

Fig. 1

Fig. 2

Fig. 3

Fig. 4

Fig. 5

Fig. 6

FIG. 1 is a front elevational view of the vehicle toy showing my new design; and

FIG. 2 is a rear elevational view thereof; and

FIG. 3 is a top and right side perspective view thereof; and

FIG. 4 is a bottom plan view thereof;

FIG. 5 is a right side elevational view thereof; and

FIG. 6 is a left side elevational view thereof.

I claim:

The ornamental design for vehicle toy, as shown.
